UNITED STATES PATENT OFFICE

2,428,043

METHOD OF MANUFACTURING METAL ELECTRIC RECTIFIERS

Arthur Mackenzie Searle, London, England, assignor, by mesne assignments, to International Standard Electric Corporation, New York, N. Y., a corporation of Delaware

Application August 16, 1943, Serial No. 498,753
In Great Britain October 2, 1942

5 Claims. (Cl. 117—38)

1

The present invention relates to the manufacture of metal rectifiers used for electrical alternating current circuits, but more particularly to the manufacture of instrument rectifiers where a very high reverse impedance may be required.

The metal rectifier is well known to consist of a metal disc or base to one surface of which is applied a layer of rectifying material (such as selenium or copper oxide or the like). A metal surface electrode is sprayed or otherwise applied to the upper surface of the rectifying material to make contact therewith. When it is desired that the impedance of the rectifier in the backward direction shall be very high, say of the order of 1 megohm, the area of the rectifying material must be made very small, for example, of the order of one or two square millimetres; and in order to avoid the difficulties associated with handling very small parts in manufacture, it is usual to employ discs of considerably larger area than would otherwise be necessary, and to coat or render active only a relatively small proportion of the area. As it is also common practice to spray the coatings through masks it is found that unless special care is taken to clean the masks after each spraying operation a progressive change in the area defined by the mask occurs because the mask itself becomes coated with the spraying material which spreads over the edges thus tending to increase the area blocked out. This may result in very large percentage changes in the active area of a small instrument rectifier.

The present invention seeks to overcome this difficulty by a manufacturing process in which it is not necessary to clean the masks after each spraying operation the coatings being so shaped that the progressive changes occurring in one mask are compensated by similar changes occurring in another subsequently used mask.

The invention accordingly comprises the method of manufacturing successively a plurality of metal rectifiers which for each rectifier comprises applying a layer of rectifying material to a base, spraying an insulating coating through a first mask on to the rectifying layer, and then spraying a conducting coating thereon through a second mask; the masks being so designed and located for spraying that the conducting coating makes contact with the rectifying layer over two or more isolated areas the sum of which is substantially independent of the progressive changes in the coating areas of successive rectifiers which result from the coating of the masks by the spraying material.

2

The invention will be described with reference to the accompanying drawing in which:

Fig. 1 shows a plan view of a metal rectifier manufactured according to the invention;

Fig. 2 shows an elevation of the rectifier; and

Figs. 3 and 4 show the shapes of two spraying masks used in manufacturing the rectifier.

The rectifier shown in Figs. 1 and 2 comprises a metal base 1 having on its upper surface a layer 2 of rectifying material (selenium, copper oxide, etc.). On the upper surface of the rectifying material is sprayed a layer or coating 3 of insulating material which is circular except for two approximately rectangular areas 5, 6, symmetrically placed on either side of, and projecting towards, the centre of the disc.

A conducting circular surface electrode 4 of smaller diameter is then sprayed on top of the insulating layer and makes contact with the rectifying layer only over the approximately rectangular areas 7 and 8 which together define the active area of the rectifier. Contact may be made with the surface electrode 4 in any convenient way, not shown.

20 The insulating coating 3 is sprayed on to the rectifying layer 2 through a mask 9, shown in Fig. 3, which consists of a thin plate having a circular hole with a diameter equal to the desired diameter of the layer 3, but having two inwardly projecting rectangular tongues 15 and 16, which define the areas 5 and 6 which are left uncoated. It will be evident that if the mask 9 is used for spraying a large number of rectifiers in succession without cleaning the 25 coating deposited on the mask will gradually enlarge the effective area of the tongues 15 and 16, so that unless appropriate measures are taken, the active areas 7 and 8 of successively manufactured rectifiers will increase, and may soon become greater than the permissible limit.

According to the invention, the surface electrode 4 is sprayed on top of the insulating layer through another mask 10 shown in Fig. 4, having a circular hole equal in diameter to that desired 30 for the electrode. If this mask is used continuously without cleaning, the deposit thereon will progressively reduce the area of the central hole and this will progressively reduce the distance from the centre of the outer edges of the active areas 7 and 8. This, it will be seen, is in the direction to compensate for the progressive increase in the uncoated areas 5, 6 due to the changes in the mask 9. By suitably dimensioning the coatings 3 and 4, the two effects may be 35 made to neutralize one another, so that the active

areas 7 and 8 on different rectifiers remain practically constant in a batch coated in succession without cleaning the masks.

It will be evident that the surface of the rectifying material may be divided up into more than two active areas, if desired, by providing a mask 9 having any number of similar inwardly projecting tongues like 15 and 16, but they should preferably be symmetrically arranged round the centre. With any number of such areas, it will only be necessary to register the masks 9 and 10 approximately correctly, for with a small amount of eccentricity, although the active areas like 7 and 8 will not all be equal, their sum will not be much changed, since some will be increased and others decreased; and moreover, the compensating effect will likewise be little affected.

It will be apparent, therefore, that the process described will enable a series of rectifiers to be manufactured within relatively close limits without the necessity for constant cleaning of the masks 9 and 10 or for accurate registration thereof, both of which requirements have hitherto been sources of increased cost in the manufacture of large quantities of rectifiers.

What is claimed is:

1. The method of manufacturing successively a plurality of metal rectifiers which for each rectifier comprises; applying a layer of rectifying material to a base, spraying an insulating coating through a first mask on to the rectifying layer, and then spraying a conducting coating thereon through a second mask; the masks being so designed and located for spraying that the conducting coating makes contact with the rectifying layer over two or more isolated areas, the sum of which is substantially independent of the progressive changes in the coating areas of successive rectifiers which result from the coating of the masks by the spraying material.

2. The method according to claim 1 in which the first mask is designed to define a circular coating area having a plurality of similar symmetrically arranged inwardly projecting areas which are uncoated.

3. The method according to claim 1 in which the second mask defines a circular coating area which is smaller in diameter than the circular area defined by the first mask.

4. The method according to claim 1 in which the first mask is designed to define a circular coating area having a plurality of similar symmetrically arranged inwardly projecting areas substantially rectangular in shape which are uncoated.

5. The method of manufacturing successively a plurality of rectifiers which for each rectifier comprises: applying a layer of rectifying material to a base; applying a coating of insulation on the rectifying layer through a mask which has an enclosed opening into which an area of the mask projects; and then applying a conducting coating through a second mask having an enclosed opening made to overlie the insulating coating and at least a portion of said projecting area.
